UNITED STATES PATENT OFFICE.

WILLIAM F. C. STANBROUGH, OF CARTHAGE, AND LYNDEN F. LASCELLE, OF SPRINGFIELD, MISSOURI.

ATTACHMENT FOR HYDROCARBON-ENGINES.

1,314,763.

Specification of Letters Patent. Patented Sept. 2, 1919.

Application filed December 21, 1916. Serial No. 138,294.

To all whom it may concern:

Be it known that we, WILLIAM F. C. STANBROUGH and LYNDEN F. LASCELLE, citizens of the United States, residing, respectively, at Carthage and Springfield, in the counties of Jasper and Green, State of Missouri, have invented a new and useful Attachment for Hydrocarbon-Engines, of which the following is a specification.

- 10 This invention relates to attachments for hydrocarbon engines, one of its objects being to provide a simple form of device which can be used in connection with different types of automobile engines and whereby 15 vapor generated within the radiator of the automobile can be conducted in desired quantities to the manifold where it is mixed with the gas to form a highly explosive mixture.
- 20 A still further object is to provide simple and efficient means convenient to the driver whereby the supply of moisture to the manifold can be minutely controlled, it being thus possible to maintain the engine at a 25 desired efficiency irrespective of the climatic conditions. It is a well known fact that when the atmosphere is heavily laden with moisture, hydrocarbon engines attain greater efficiency than where the air is dry and rare, 30 this being due to the fact that a larger percentage of moisture is admitted to the carburetor under one condition than under the other. In order that the same desirable proportions of gas and moisture may be obtained 35 irrespective of atmospheric conditions, the present invention has been devised.

With the foregoing and other objects in view which will appear as the description 40 proceeds, the invention resides in the combination and arrangement of parts and in the details of construction hereinafter described and claimed, it being understood that changes in the precise embodiment of the 45 invention herein disclosed, can be made within the scope of what is claimed, without departing from the spirit of the invention.

In the accompanying drawings the preferred form of the invention has been shown.

50 In said drawings:

Figure 1 is a side elevation of the attachment applied to an automobile, parts of the automobile being shown in elevation and the radiator being shown partly in section.

Fig. 2 is an enlarged section through the 55 controlling valve of the attachment.

Fig. 3 is an enlarged vertical section through the connection between the attachment and the overflow pipe and also through the overflow valve. 60

Fig. 4 is a section on line 4—4 Fig. 3.

Fig. 5 is a view partly in plan and partly in section of the nozzle employed for directing the moisture into the manifold. 65

Fig. 6 is a top plan view of the wire actuating element.

Fig. 7 is a side elevation of the structure shown in Fig. 6, the lever being shown in a position at right angles to that shown in Fig. 6. 70

Referring to the figures by characters of reference A designates the radiator of an automobile and B the manifold of the engine, the same being of any preferred type. The radiator has the usual overflow tube C 75 extending from the upper portion thereof and downwardly to a point close to the bottom of the radiator.

The device constituting the present invention is designed as an attachment and 80 can be applied readily by an ordinary mechanic at a slight cost. The attachment includes a tapered nozzle 1 shown in Fig. 5 and which nozzle has a nipple 2. This nozzle is adapted to be screwed into an opening 3 formed in the manifold B and is coupled to a valve casing 4 having a rotary valve 5 therein the stem 6 of which has a radial arm 7. A tube 8 is extended from the valve casing and has a coupling 9 to 85

which is attached one end of a spring 10, the other end of the spring being attached to the arm 7 so that the valve is thus held normally in closed position as shown in Fig. 2. The coupling 9 serves to connect the tube 8 to a flexible tube 11 of metal or the like 90 which can be readily bent to adapt the attachment to engines of different forms. This tube is coupled to a tubular member 12 having a tapered tubular extension 13 at one end adapted to be forced up into the lower end of the overflow pipe C. A valve casing 14 is extended upwardly from the member 12 and has a removable cap 15. Within this casing is arranged a ball valve 16 (see Figs. 3 and 4) and which valve is 95 normally mounted on a seat 17. Outflow apertures 18 are provided within the valve

casing 14 but communication between these apertures and the interior of the tubular member 12 is normally shut off by the valve 16. However, when the valve is raised, communication is established between the interior member 12 and the apertures.

5 A collar 19 is adapted to be clamped upon the overflow pipe C and another collar 20 is adapted to be secured upon the tubular member 12. The two collars are then connected by a tie wire 21 or the like whereby the member 12 is held against downward movement relative to the overflow pipe C.

Attached to the dash D is a guide bracket 22 and extending from this bracket and through the dash is a flexible tubular guide 23 which can be made of coiled wire and which, in the form illustrated, is extended along the steering post E and to an attaching plate 24 which straddles the steering post. This plate is held firmly on the steering post by a U-bolt 25. Secured to the plate 24 is a lever 26 carrying a spring controlled dog 27 adapted to engage between radial ribs 28 carried by the plate 24 and which cooperates with the dog to hold the lever 26 against movement. The ribs 28 are preferably formed on a flange 29 formed with the plate 24. Secured to lever 26 is one end of a controlling wire 30, this wire being slidably mounted within the tube 23 and bracket 22 and being connected to the arm 7.

It is to be understood that instead of 35 mounting the lever 26 on the steering post E where it can be quickly reached by the hand grasping the steering wheel, the said plate can be attached to the dash 31 as shown in Fig. 7.

40 Under ordinary conditions the valve 5 is closed and, therefore, any vapor generated within the radiator will not be sucked into the engine. However, by means of lever 26 the wire 30 can be actuated to shift arm 7 45 and move the valve 5 to open or partly open position. Thus vapor generated within the radiator will be sucked through the overflow pipe C and the member 12 into the tube 11, thence through the nozzle 1 into the manifold where it will mix with the mixture of 50 gas and air and increase the efficiency of the explosive mixture. In fact it has been found in practice that where vapor is thus used, a smaller amount of gas can be employed than where only a mixture of air and gas is used. Consequently a considerable saving of fuel is effected. By provid-

ing this means of adjustment the engine will operate efficiently under all climatic conditions and a minute adjustment can always 60 be effected for controlling the supply of moisture to the explosive mixture. Obviously when moisture is being sucked into the engine the valve 16 will be held to its seat. Should the radiator overflow from any 65 cause, the force of the water will lift the valve off of its seat and the overflow will pass out through the openings 18. Should it be desired to draw an amount of water into the engine as when carbon is to be blown 70 therefrom, the radiator can be caused to slightly overflow so as to leave an amount of water in the member 12. Therefore during the suction set up by the engine, this water will be drawn into the manifold where it 75 will mix with the air and gas and then be directed into the explosion chambers.

What is claimed is:—

1. An attachment for hydro carbon engines including a valved flexible tube, a nozzle at one end for attachment to an engine manifold, a tubular member at the other end having a tapered extension adapted to be wedged into the overflow pipe of a radiator, said member having an outflow aperture in 80 the top portion thereof, a check valve for said aperture, and means adapted to be connected to the overflow pipe for supporting the tapered extension in said pipe.

2. As a complete article of manufacture 90 an attachment for hydro carbon engines comprising a flexible tube, a normally closed valve carried thereby, flexible means for operating the valve, a nozzle at one end of the tube for attachment to the manifold of 95 an engine, a tubular member at the other end of the tube having an outflow aperture in the tip portion thereof, a check valve for said aperture, a tapered extension upon the member and adapted to be wedged into the 100 end of the overflow pipe of a radiator, and means for attachment to said overflow pipe for supporting the extension in the pipe.

In testimony that we claim the foregoing as our own, we have hereto affixed our signatures in the presence of two witnesses.

WILLIAM F. C. STANBROUGH.
